UNITED STATES PATENT OFFICE.

FRITZ ROSSBACH-ROUSSET, OF TEMPELHOF, NEAR BERLIN, GERMANY.

ROTARY ENGINE.

No. 895,043.

Specification of Letters Patent.

Patented Aug. 4, 1908.

Application filed November 6, 1907. Serial No. 401,016.

To all whom it may concern:

Be it known that I, FRITZ ROSSBACH-ROUSSET, a subject of the Emperor of Germany, and a resident of Tempelhof, near Berlin, in the Empire of Germany, have invented certain new and useful Improvements in Rotary Engines and Pumps, of which the following is a specification.

My invention relates to rotary machines 10 adapted for use either as engines or as pumps or blowers, according as they are operated by a driving fluid, such as steam, or by power from a motor.

The present invention has especial reference to structures employing a plurality of pistons rotating intermittently and connected successively with the shaft or other permanently rotating part. In devices of this character, considerable difficulty has 20 been experienced in avoiding jerky motion and excessive temporary strains on the transmitting mechanism interposed between the pistons and the permanently rotating part. To overcome these defects, I have 25 devised a novel arrangement and connection of elements, particularly of the transmitting mechanism, and I will now describe a few practical embodiments of my invention with reference to the accompanying drawings, in 30 which

Figure 1 is a longitudinal vertical section through one form of my invention; Fig. 2 is a cross section thereof on line A—B of Fig. 1; Fig. 3 is a longitudinal section of another 35 form of the machine; Fig. 4 is a cross section thereof on line C—D of Fig. 3; Fig. 5 is a longitudinal section of a third form of construction, Fig. 6 is a cross section on line E—F of Fig. 5. Figs. 7 and 8 are perspective views of the two pistons 3, 4, employed 40 in the construction illustrated by Figs. 1 and 2; and Figs. 9 and 10 are perspective views of the two pistons 3^b, 4^b employed in the construction shown in Figs. 5 and 6.

45 The stationary casing 1 of the machine is provided with inlets 7 and outlets 10 for the driving or propelled fluid. A shaft 2 is journaled air-tight in the center of the casing and on this shaft are mounted loosely rotary pistons 3 and 4. Each of the pistons 3, 4, is adapted to be held stationary at times between the ports 7 and 10, by means of a locking member or slide 9, operated at the proper moment by means of suitable mechanism 50 such as a cam 17 mounted on the shaft 2 and a lever 8 controlled by said cam.

So far as above described, the construction shown in Figs. 1 and 2 need not differ materially from usual ones, although the pistons 3, 4, have certain novel features fully set 60 forth hereinafter.

The well-known general operation of this machine, when used as a motor, is as follows: In Fig. 2 the piston 4 is shown locked by the slide 9, and forms an abutment for the steam or other medium admitted at 7. The piston 3 being loose, is rotated in the direction of the arrow until it comes in contact with the stationary piston 4. Immediately before this, the locking member 9 is withdrawn 70 through the action of the cam 17 or otherwise so that the impact of the piston 3 against the piston 4 throws the latter forward beyond the port 7, as indicated in dotted lines, while at the same time the piston 75 3 is locked by the slide 9 in the same position in which Fig. 2 shows the piston 4. The pistons therefore rotate alternately and intermittently. To transmit this intermittent motion to a rotary member, for instance 80 the shaft 2, in such a manner that it will rotate continuously and with substantial uniformity of speed, I have provided the following improved mechanism: The two pistons 3, 4, which preferably overlap in the 85 manner indicated in Fig. 1, have rigidly secured to their hubs 5 and 6, bevel gear wheels 12 and 13 respectively, co-axial with the shaft 2. The latter is provided with a rigid hub 14 carrying radial studs 15 on which are 90 mounted to turn bevel pinions 11 each of which permanently engages both bevel gear wheels 12 and 13. The details of construction may, of course, be varied. On the shaft 2 may be mounted a pulley 16 to receive or deliver power, as the case may be. The operation of this transmitting mechanism will be understood readily. If for instance the piston 4 is stationary and the piston 3 in motion (see Fig. 2) the rotating 95 bevel gear wheel 12 will not only turn the bevel pinions 11 about their axes or studs 15, but owing to the engagement of said pinions with the stationary bevel gear wheel 13 the pinions 11 will roll on said stationary wheel 100 and thus move bodily together with the studs 15, hub 14 and shaft 2, in the same direction in which the piston 3 rotates. In accordance with the well-known operation of planetary gearing, the rotary speed of the shaft 110 2 will be one-half of that of the piston 3. When this piston collides with the piston 4

(released at that moment by the withdrawal of the locking member 9), both pistons and the shaft move in unison for a short interval, that is, until the slide 9 locks the piston 3. 5 During this interval the momentum of the shaft and of the heavy parts connected therewith, causes the two pistons and the shaft to rotate at practically one-half the piston speed. Then the steam or other medium 10 will exert a driving action on the piston 4 and gear wheel 13, while the gear wheel 12 is held stationary and the planetary pinions 11 roll on said gear wheel 12, causing the shaft 2 to rotate at one-half the speed of the 15 piston 4, in practically the same manner and in the same direction as before. Thus the shaft is continuously rotated in the same direction at a practically constant rate of speed, and without any heavy jerks such as 20 might break the teeth of the gear wheels, it being noted that the pinions 11 are in mesh permanently with the gear wheels 12 and 13. Instead of bevel gearing, I might employ 25 spur gears. The motor is reversible by simply altering the fluid connections so that 10 will become the inlet and 7 the outlet.

In Figs. 3 and 4 the casing 1^a has two diametrically opposite inlets 7^a and two outlets 10^a between each pair of which is located 30 a locking member 9^a for the four pistons 3^a, 4^a, the two locking members being operated similarly in unison by cam mechanism (not shown) which may be of the same character as the one shown in Fig. 1 at 17, 8. Each of 35 the four pistons is mounted loosely on the shaft 2^a. The shaft 2^a in this case has two hubs 14^a with radial studs 15^a for pinions 11^a. Each of the pistons 3^a has rigidly secured to it a gear wheel 12^a, and each of the 40 pistons 4^a, a gear wheel 13^a. Each of the pinions 11^a meshes with one of the gear wheels 12^a and with the adjacent gear wheel 13^a. The operation is very similar to that described above, it being understood that 45 the pistons of the same pair (3^a or 4^a) are locked and released at the same time by the slides or locking members 9^a.

The construction illustrated by Figs. 5 and 6 has the planetary gearing arranged 50 outside the casing 1^b. One of the overlapping pistons 3^b, 4^b, is rigidly secured by its hub 5^b to the shaft 2^b, the other (4^b) has its sleeve-like hub 6^b extended considerably to the outside of the casing and provided 55 with a gear wheel 13^b. This piston 4^b is mounted loosely on the shaft 2^b. To the latter is secured rigidly the gear wheel 12^b, and between the two wheels 12^b and 13^b I mount on the shaft loosely, the hub 14^b of 60 the pulley 16^b carrying the radial studs or spokes 15^b on which are mounted the pinions 11^b, each in mesh with the wheels 12^b and 13^b. The operation will be practically the same as above described, it being understood that the arrangement of fluid inlet 65

and fluid outlet, and of members for alternately locking and releasing the pistons, is the same in principle as in the other forms of my invention.

If instead of admitting a driving medium 70 through the inlet, power is applied to the pulley or equivalent part, the alternate rotation of pistons thus produced will create suction at one port and pressure at the other, so that the machine will in that case 75 operate as a pump or blower.

I claim as my invention:

1. The combination of the casing having ports for the admission and egress of a fluid, the pistons arranged to turn in said casing about the same axis independently of each other, the rotary member loose relatively to the pistons and co-axial therewith, means governed by the rotation of said member, for alternately locking and releasing the pistons, and planetary gearing interposed between the pistons and the rotary member. 80 85

2. The combination of the casing having ports for the admission and egress of a fluid, the pistons arranged to turn in said casing about the same axis independently of each other, the rotary member loose relatively to the pistons and co-axial therewith, means for alternately locking and releasing the pistons, and planetary gearing interposed 90 95 between the pistons and the rotary member.

3. The combination of the casing having ports for the admission and egress of a fluid, the pistons arranged to turn in said casing about the same axis independently of each other, the rotary member loose relatively to the pistons and co-axial therewith, means for alternately locking and releasing the pistons, a hub connected rigidly with said rotary member and provided with radial studs, pinions mounted to turn on said studs, and gears rigidly connected with the respective pistons and in permanent mesh with said pinions. 100 105

4. The combination of the casing having ports for the admission and egress of a fluid, the pistons arranged to turn in said casing about the same axis independently of each other, the rotary member loose relatively to the pistons and co-axial therewith, means for alternately locking and releasing the pistons, a hub connected rigidly with the rotary member, pinions carried by said hub to revolve therewith and also mounted to rotate about individual radial axes, and gears rigidly connected with the pistons and in permanent mesh with said pinions. 110 115 120

5. The combination of the casing having ports for the admission and egress of a fluid, the pistons arranged to turn in said casing about the same axis independently of each other, a rotary member, pinions carried by said member to revolve therewith and also mounted to rotate about individual radial axes, gear wheels, in permanent mesh with 125 130

said pinions and operatively connected with the respective pistons, and means for alternately locking and releasing the pistons.

6. The combination of the casing having a plurality of inlet ports and of outlet ports arranged at different points of its periphery, pistons equal in number to said ports and mounted to rotate within the casing, means for alternately locking and releasing the pistons, a rotary member, and sets of planetary gearing connecting said member with the respective pistons, one set being connected with two adjacent pistons, and the other set with the next two pistons.

15 7. The combination of the casing having

ports for the admission and egress of a fluid, pistons arranged to turn in said casing about the same axis and constructed to overlap one another, a rotary member, planetary gearing interposed between said member and the pistons, and means for alternately locking and releasing the pistons.

In testimony whereof, I have hereunto set my hand in the presence of two subscribing witnesses, this 22nd day of October, 1907.

FRITZ ROSSBACH-ROUSSET.
